CLAIM

The ornamental design for a phone case, as shown and described.

DESCRIPTION

FIG. 1 is a front, right side, and top perspective view of a phone case showing my new design;

FIG. 2 is a rear, left side, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 3; and,

FIG. 12 is an enlarged view of portion 12 shown in FIG. 5. The dashed broken lines in the drawing figures form no part of the claimed design and depict portions of the phone case that form no part of the claimed design. The dot-dash broken lines in FIGS. 1, 3, 5, and 9-12 form no part of the claimed design and delineate portions of the phone case, including claimed subject matter, that are shown on an enlarged scale in FIGS. 9-12.
